UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

MULTIPLE-THREAD TENSION DEVICE FOR SEWING MACHINES.

Application filed December 7, 1922. Serial No. 605,351.

To all whom it may concern:

Be it known that I, ANDREW B. CLAYTON, a citizen of the United States, residing at Union, in the county of Union and State of 5 New Jersey, have invented certain new and useful Improvements in Multiple-Thread Tension Devices for Sewing Machines, of which the following is a specification, reference being had therein to the accompanying 10 drawings.

This invention relates to multiple needle sewing machines and has for an object to provide a simple and compact thread-tension device which will handle a plurality of 15 threads with substantially equal treatment.

Another object of the invention is to provide a multiple-thread tension device of 20 compact and simplified construction which is adapted to receive any desired number of 25 thread-tension elements with which it may be supplied.

Another object of the invention is to provide an intermittent multiple-thread tension device or nipper particularly adapted for 30 handling a plurality of looper-threads in a multiple-needle, multiple-looper sewing machine.

According to the present improvement there are provided two groups or assemblies 35 of spaced thread-tension element; each assembly preferably comprising a support to which the tension elements are secured in spaced and stacked relation by means of suitable separators and fastening means. The two assemblies of tension elements are 40 so cooperatively related that the elements of one assembly or stack extend into the spaces between or, in other words, are interleaved with the elements of the other assembly or stack, whereby pairs of coacting tension elements are provided. By shifting or 45 rocking one of the tension-element supports the tension-elements of one group are simultaneously shifted toward or away from the respective tension-elements of the other group to tension or release the threads passing between the respective pairs of tension-elements.

In the accompanying drawings Fig. 1 is a 50 fragmentary side elevation of a sewing machine embodying the invention. Fig. 2 is a plan view of the tension device, shown in Fig. 1. Fig. 3 is a section on the line 3, 3, Fig. 1. Fig. 4 is a disassembled perspective

view of the device. Fig. 5 is a side elevation of one group of tension-elements shown in Fig. 3. Fig. 6 is a plan view of one pair of coacting tension-elements, and Fig. 7 shows a modification of the invention.

In the preferred embodiment of the invention, as illustrated in Figs. 1 to 6 inclusive, 60 1 represent the tension support which may be secured to the bed 2 of a sewing machine by means of screws 3. The support 1 is preferably formed with a seat 4 for the squared lower or shank ends of a stack of similar tension-elements or nipper-springs 5 held in spaced relation by suitable separators 6 through which and the springs 5 pass the holding screw 7; the latter clamping the stack of nipper-springs 5 against the vertical wall or clamping surface 8 of the stationary support 1.

Projecting from the side of the support 1 is a bearing pin 9 on which is journaled for 75 rocking movement the support 10 having a seat 11 for the squared lower or shank ends of a second stack of similar tension-elements or nipper-springs 12 which are held in spaced relation by suitable separators 13 equal in thickness to the separators 6. A screw 13' passes through the springs 12 and separator 13 and clamps the stack against the clamping surface 13'' on the movable support 10. The upper end- 80 portions of blades of the nipper-springs 12 are preferably offset from their respective shanks and are thus adapted to be interleaved with the nipper-springs 5 to form a plurality of pairs of coacting tension-elements. Preferably, each of the nipper-springs 5 has edge lips 14 bent at right angles to the plane of the spring proper and slotted at 15 to form thread-guides. The blade of each nipper-spring 12 is received 85 between the bent lips 14 of its respective coacting springs 5, as shown in Fig. 6.

In the specific embodiment of the invention illustrated in Figs. 1 to 6 inclusive, the tension device is of the intermittently 100 operated type and the movable support 11 has secured thereto by a screw 16 an arm 17 having a lateral extension 18 projecting across the end of a plunger-pin 19 slidably mounted in the apertured lug 20 forming an extension of the stationary support 1. The plunger-pin 19 has a head 21 which is engaged by the actuating cam 22

on the main-shaft 23 of the sewing machine. A coil spring 24, one end of which is anchored in the movable support 10 and the other end to the collar 25 fixed 5 to the bearing pin 9, yieldingly rocks the support 10 in a direction to separate the movable tension-elements 12 from their respective coacting elements 5 and retain the plunger-pin 19 in engagement with its actuating cam 22.

It will be observed that the several tensions will be shifted simultaneously and to substantially equal extents by the action of the cam 22 and plunger-pin 19 on the rock- 10 ing support 10. The pressure on each of the tension-elements is transmitted to it independently of any other tension-elements, and the tensions exerted on the threads by the several tension-elements are equal. In 15 other words, the present tension device treats the several threads equally in all respects, as is usually desirable in sewing machines having a plurality of needles or loops.

25 The tension device shown and described in Fig. 1 to 6 inclusive is of the intermittently operated type particularly adapted to tension or nip the respective threads with sufficient intensity to prevent slippage of the threads. The invention is not to be understood as limited to tension devices of the intermittently operated type, however, as it is useful in constant tension devices such as shown in Fig. 7, wherein an adjusting screw 26 and lock-nut 27 are substituted for the cam-operated plunger 19. The device shown in Fig. 7 is in all other respects substantially the same as that shown in Figs. 1 to 6 inclusive. By ad-

justing the screw 26 the several tensions 40 may be adjusted simultaneously and to equal extents.

Having thus set forth the nature of the invention, what I claim herein is:

1. A multiple thread-tension device comprising a pair of relatively movable supports, a series of interleaved thread-nipping elements mounted alternately in spaced relation on said supports, and means for relatively moving said supports to shift the 50 nipping elements carried by one support toward or away from the nipping elements carried by the other support.

2. A multiple thread-tension device comprising a stationary support, a movable support pivoted on said stationary support, a series of thread-nipping elements in the form of nipper-springs mounted in spaced relation on said stationary support, a second series of nipper-springs mounted 60 in spaced relation on said movable support and interleaved with the springs of said first mentioned series, and means for moving said movable support.

3. A multiple thread-tension device comprising a pair of relatively movable supports each having angularly related clamping and seating surfaces, and a series of interleaved flat elongated thread-nipping elements carried by said supports, the elements carried by each support being secured to a clamping surface of such support with their ends in engagement with a seating surface of such support.

In testimony whereof, I have signed my name to this specification.

ANDREW B. CLAYTON.
